INVENTOR
Frank M. Ashley

UNITED STATES PATENT OFFICE.

FRANK M. ASHLEY, OF BROOKLYN, NEW YORK.

FOUNTAIN PEN.

Application filed October 30, 1926. Serial No. 145,120.

My invention relates to fountain pens.

The object of my invention is to provide an improved construction of the self-filling type of pen, that may be filled easily, has 5 a large reservoir for ink, may be made entirely of hard vulcanized rubber, is provided with a smaller or auxiliary reservoir and a valve to close communication between the large reservoir and smaller reservoir. 10 Also a pen in which a grip surface is provided for the user having a reduced diameter relative to that of the barrel of the pen and a part of which also serves as a friction surface to hold the pen cap.

15 It is not necessary that all of the above enumerated features of construction be incorporated in a single pen, as in making them for the market certain of the above features of construction may be omitted 20 if desired, but the specific combination of elements shown and claimed herein may be incorporated in a pen construction and in such a manner be protected by patent.

Referring to the drawings which form a 25 part of this specification:

Fig. 1 is an exterior view of a pen drawn to full scale, showing a pen having a large diameter of barrel of normal length and large ink capacity.

30 Fig. 2 is a longitudinal sectional view of a pen embodying my invention.

A, indicates the barrel of the pen, which is provided with a reservoir A' having a smooth cylindrical inner wall A². The inner 35 diameter of the barrel is enlarged at A³ to provide an annular passage A⁴ for ink between the outer surface of the piston B and barrel at this point. C, indicates a pen-section which may be made integral with the 40 barrel A, if desired, or may be connected thereto by a thread in the usual manner. The pen-section is reduced in diameter at C' and provided with a smooth surface to hold the cap of the pen (not shown) by friction. A gripping surface for the fingers 45 of the user is provided as illustrated at C², and a smooth surface at C³ to readily shed the ink after the filling operation.

A plug, preferably made separable from 50 the barrel and connected thereto by a threaded joint at D², is provided with a friction surface C⁴ for the cap, and with a

bore D' and a hole D³ of smaller diameter than the bore through which extends a piston-rod E. Cork F, or other suitable 55 packing material is fitted in the bore around the piston-rod as shown, and a packing nut G, which engages a thread D⁴ in the bore, compresses the packing and is screwed into the bore beyond the outer end thereof far 60 enough to permit the threaded end H' of the rod-nut H, connected to the piston-rod E, to engage the thread D⁴. The piston B, is connected to the piston-rod at E', and adjusted relative to the rod-nut H at such 65 a distance that when the inner end of the rod-nut is screwed or positioned just outside of the bore D', the back end of the piston will not close the passage A⁴, but when moved a short distance further it will close 70 this passage and shut off the ink from flowing from the reservoir to the opposite side of the piston B and at the same time cause the free end of the tube J to keep the hole N in the feed-plug covered to prevent in- 75 gress of air to the upper end of the reservoir A'. Connected to the front end of the piston B, is a small tube J, which may be made of hard rubber or glass, and the piston is provided with one or more passages B' 80 which lead from the reservoir A' to the open end of the tube J, located in the piston as illustrated. A feed-plug K, is located in the pen-section C and extends nearly to the inner end thereof as shown, and a space 85 L is provided between the inner end of the feed-plug and including the space A⁴ forming the annular passage, provides an auxiliary or feed reservoir for ink while the main reservoir A' is closed by the rear end 90 of the piston.

The front end of the piston abuts the rear end of the pen-section C to provide a valve, which is closed when the rod-nut is screwed fully into the bore D³, and in this 95 position the auxiliary chamber L is reduced in its size but still holds enough ink to serve for writing a number of words such as signatures, and therefore it is not necessary to unscrew the rod-nut every time the 100 pen is used. The provision of the auxiliary reservoir L, serves a further important function, viz: it prevents "flooding", which often occurs when a large reservoir becomes

nearly empty, and also when heat is applied to the barrel on a cold day and the air in the barrel is caused to expand and force the ink from the reservoir. In the present pen, 5 the use of the auxiliary reservoir permits use of the pen without opening the main reservoir, except to refill the auxiliary from time to time.

The feed-plug K is provided with the 10 usual feed-duct K' to feed the pen-point M, and is also provided with a central bore K², in which the tube J fits in close sliding engagement with the wall thereof. A hole N leads through the feed-plug to form a passage 15 for air exhaust from the reservoir A' and as a filling passage through which ink may flow into the reservoir.

The outer end of the tube covers the hole N to close the passage just before the passage 20 A' is opened on the inward or filling stroke of the piston B. A film of ink around the tube J adjacent the hole N prevents any air from passing from the atmosphere to the passage through the hole N, even though the 25 tube is not a perfect sliding fit.

An important feature of this construction is that the piston does not have to be a tight fit in the barrel A, since the air in the reservoir flows freely therefrom through the 30 passages B' and tube J to the outlet hole N, on the outward stroke of the piston, and the ink flows into the reservoir through the same passages, on the inward stroke of the piston while the ink that has been drawn into the 35 pen through the ink-duct K' on the outward stroke of the piston is forced from the pen on its inward stroke, thus causing the ink to flow through the ink-duct twice to clean the same, each time the filling operation is 40 carried out, it being assumed that the end of the feed-plug and pen-section is submerged in the ink supply receptacle during the filling operation, which will completely fill the main and auxiliary reservoir.

45 It is obvious that the main reservoir may be completely filled by submerging the pen during the inward or filling-stroke of the piston only, the air-expelling stroke leaving the cylinder free from air when the piston 50 abuts the inner end of the plug D. To permit the piston to move easily with a minimum of friction, concentric grooves are cut in the cylindrical surface, providing thin edge portions which contact the inner wall 55 of the barrel and make an easy working tight sliding joint therewith, the edge surface of each edge portion making in effect, a separate piston, and the grooves filling with ink, serve also to provide an efficient joint. 60 The removable plug D permits the packing and adjacent parts to be assembled before the piston is placed in the barrel of the pen.

It is thought that the foregoing description is ample to instruct a person skilled in

this art to fully understand and use the invention disclosed. 65

Having thus described my invention I claim as new:

1. A fountain pen comprising a barrel having its outer end closed to form a reservoir therein, a piston-rod extending through said closed end, a piston movable by said rod, a tube connected to said piston in open communication with said reservoir, a pen-section connected to said barrel, a feed-plug in said pen-section having a feed-duct formed therein leading to said reservoir, and a bore leading to the atmosphere into which said tube fits in sliding relation; the construction being such that air is expelled from the reservoir on the outward stroke of the piston and ink may flow into the reservoir on the inward stroke thereof. 70 75 80

2. A fountain pen comprising a barrel having its outer end closed to form a reservoir therein, a pen-section connected to the opposite end of the barrel, a feed-plug provided with a feed-duct, and with a bore leading to the atmosphere, a piston, a tube extending therefrom into said bore in open communication with the atmosphere and with said reservoir, a passage leading from said reservoir to said feed-duct and a piston-rod connected to said piston and extending through said closed end of the barrel. 90 95

3. A fountain pen comprising a barrel having its outer end closed by a removable plug having packing material therein to form a reservoir therein, a pen-section connected to the opposite end of the barrel, a feed-plug provided with a feed-duct, and with a bore leading to the atmosphere, a piston, a tube extending therefrom into said bore in open communication with the atmosphere and with said reservoir, a passage leading from said reservoir to said feed-duct and a piston-rod connected to said piston and extending through said closed end of the barrel. 100 105

4. A fountain pen comprising a barrel which serves as a reservoir, and having its outer end closed by a plug having a threaded bore, a pen-section connected to the opposite end of the barrel, a feed-plug provided with a bore having an opening in one side thereof leading to the atmosphere, a piston, a tube extending therefrom into said bore in open communication with the atmosphere through said opening in the feed-plug, and with the reservoir, a passage leading from said reservoir to said feed-duct, a piston-rod connected to said piston and extending through said plug, a rod-nut on said rod having its inner end so positioned relative to the opening in the feed-plug that the free end of the tube will cover the said opening therein until the piston has closed the passage leading from the said reser- 110 115 120 125

voir to the feed-duct in said plug, when a further movement of the rod will cause the opening to be uncovered, for the purpose set forth.

5. A fountain pen comprising a barrel which serves as a reservoir, and having its outer end closed by a plug having a threaded bore, a pen-section connected to the opposite end of the barrel, a feed-plug 10 provided with a bore having an opening in one side thereof leading to the atmosphere, a piston, a tube extending therefrom into said bore in open communication with the atmosphere through said opening in the feed-plug, and with the reservoir, a passage leading from said reservoir to said feed-duct, a piston-rod connected to said piston and extending through said plug, a rod-nut on said rod having an inner threaded 20 end so positioned relative to the opening in the feed-plug that the free end of the tube will cover the said opening therein until the piston has closed the passage leading from the said reservoir to the feed-duct in said plug, when a further movement of the rod will cause the opening to be uncovered, for the purpose set forth.

6. A fountain pen comprising a barrel having a reservoir therein, a plug at one end thereof, a pen-section at the opposite end thereof, a feed-plug having a feed-duct, and a central bore therein with an opening in one side leading to the atmosphere; a piston-rod extending through said plug, a piston on said rod having a passage therethrough, a tube connected to the piston in open communication with said passage in the piston and extending through said bore beyond said opening therein, a passage 40 formed in the barrel leading to said feed-duct, the arrangement of the parts being such that the movement of the piston will close the passage leading to the feed-duct and open the passage leading from the reservoir through the tube to the atmosphere.

7. A fountain pen comprising a barrel having a reservoir therein, a plug at one end thereof having its diameter reduced at its outer end and provided with a friction surface to hold a pen cap, a pen-section at the opposite end thereof having a diameter equal to that of the plug to hold a pen cap, a feed-plug having a feed-duct, and a central bore therein with an opening in one side leading to the atmosphere; a piston-rod extending through said plug, a piston on said rod having a passage therethrough, a tube connected to the piston in open communication with said passage in the piston and extending through said bore beyond said opening therein, a passage 55 formed in the barrel leading to said feed-duct, the arrangement of the parts being such that the movement of the piston will

close the passage leading to the feed-duct and open the passage leading from the reservoir through the tube to the atmosphere.

8. A fountain pen comprising a barrel having a reservoir therein and closed at its outer end, a pen-section connected to the front end of the barrel, a feed-plug, a passage comprising an auxiliary reservoir formed between the main reservoir, pen-section and feed-plug, said feed-plug having a feed-duct and a central bore therein with an opening in one side thereof leading to the atmosphere; a piston-rod extending through the closed end of said barrel, a piston on said rod having a passage therethrough, a tube 70 connected to the piston in open communication with said passage in the piston and extending through said bore beyond the opening therein; the arrangement of the parts being such that the movement of the piston will close the passage leading to the feed-duct and open the passage leading from the reservoir to the atmosphere in one position of the piston and close the passage leading to the atmosphere and open the passage leading 75 to the feed-duct in another position of the piston.

9. A fountain pen comprising a barrel having a reservoir therein and closed at its outer end, a pen-section connected to the front end of the barrel, a feed-plug, a passage comprising an auxiliary reservoir formed between the main reservoir, pen-section and feed-plug, said feed-plug having a feed-duct and a central bore therein with an opening in one side thereof leading to the atmosphere; a piston-rod extending through the closed end of said barrel, a piston on said rod having a passage therethrough, a tube 80 connected to the piston in open communication with said passage in the piston and extending through said bore beyond the opening therein; the arrangement of the parts being such that the movement of the piston will close the passage leading to the feed-duct and open the passage leading from the reservoir to the atmosphere in one position of the piston and close the passage leading to the atmosphere and open the passage leading 85 to the feed-duct in another position of the piston.

10. A fountain pen comprising a main reservoir and a supplemental reservoir, an air tube extending thru said supplemental reservoir to the main reservoir, means for closing communication between said main reservoir and supplemental reservoir and means for drawing ink into said main and supplemental reservoir said means serving to expel air from said main reservoir and means for closing said air tube to prevent 100

air from flowing from the atmosphere into said main reservoir.

11. A fountain pen comprising a main reservoir, a piston, a pen-section having a supplemental reservoir formed therein, a manually operated reciprocating valve for closing communication between said main reservoir and supplemental reservoir, an air

tube extending thru said pen section and piston into said main reservoir and means ¹⁰ for drawing ink into said reservoir, and expelling the air therefrom thru said tube to the atmosphere.

In testimony whereof I have affixed my signature.

FRANK M. ASHLEY.
